UNITED STATES PATENT OFFICE.

SAMUEL E. MORRAL AND WILLIAM W. MORRAL, OF MORRAL, OHIO.

CAN-LABELING MACHINE.

No. 900,114.

Specification of Letters Patent.

Patented Oct. 6, 1908.

Application filed August 10, 1907. Serial No. 387,964.

To all whom it may concern:

Be it known that we, SAMUEL E. MORRAL and WILLIAM W. MORRAL, citizens of the United States, residing at Morral, in the 5 county of Marion and State of Ohio, have invented a certain new and useful Improvement in Can-Labeling Machines, of which the following is a specification.

The present invention is an improvement 10 upon the machine shown in the patent of the United States issued to Samuel E. and John Morral April 18, 1905, No. 787,628.

In constructing and using the machine as shown in said Patent No. 787,628 we employed a belt, designated in the said patent as 12^a, of leather to propel or draw the cans through the machine, and we found after some use that the paste accumulated on the belt to such an extent as to render it necessary to frequently stop the machine to remove the accumulation and clean the belt, as the paste on the belt would catch the label after it was wrapped part way round the can and pull it off again. Moreover, leather, 25 being of a rather porous nature, absorbed a great deal of pasty moisture, which would cause it to stretch and then it would slip on the pulleys and give a good deal of trouble, and upon drying the belt became hard and 30 stiff and would break easily. We found a belt of this kind would not be durable, and was very unsatisfactory. We also tried rubber belts and cotton belts, which gave some results like those obtained with leather belts. 35 These difficulties perplexed us greatly until we hit upon the idea of using a metallic belt and especially a belt constructed of metallic links with projections adapted to engage the cans and suitable means for guiding such 40 belt.

Our invention therefore consists in the improvements as hereinafter described and claimed.

In the accompanying drawing—Figure 1 is a side view of the machine with our improved belt attached; Fig. 2 is a top plan view with parts of the belt broken out; Fig. 3 is a detail on a larger scale showing a fraction of the belt and how it is engaged by the 45 roller; Fig. 4 is a plan view of a fraction of the belt; Fig. 5 is a side view of the belt-guiding roller.

In the several views herein, as in the views of the former patent referred to, 1 designates 50 the bed, and 1^a top rails supported above the bed, and upon which bed and top rails the

operative parts are mounted. This bed is shown to be supported upon suitable legs 1^b.

2 designates a label-holder that is slidably supported and guided by appropriate guides 60 2^a secured to the under side of the bed or runway. The label-holder is pressed up to put the labels in labeling position by means of a spring 2^b, drawing on a lever 2^c, fulcrumed on the lower end of a rigid hanger 2^d, 65 extending downward from the under side of the bed. The pressure of the spring 2^b can be regulated by means of an adjustable nut 2^e.

3 designates the labels. These are placed 70 in a pile or package on top of the label-holder, so as to be fed up and exposed through an opening in the bed, and suitable provision, as in the former patent referred to or otherwise, is made for applying the paste to them. 75 Also as in the former patent, the forward end of the uppermost label may be held down until removed by a can by means of a gravity-actuated rearwardly-extending arm 5 pivoted to swing in a vertical plane between 80 the top rails 1^a.

Journaled in suitable brackets extending laterally from the sills of the bed and the top rails are four belt-wheels 6. These belt-wheels stand or turn in a horizontal plane, 85 and passing around their rims is the paste-belt 7, which normally runs in vertical planes. The belt crosses the bed at the forward end of the machine at a point sufficiently beyond the label-holder to permit the can to make about 90 one revolution on the runway by the time it reaches the label, and the belt also crosses the rear portion of the runway at a point where the label will have been picked up and wrapped around the can. 95

Journaled in the horizontal bearings on the front and rear ends of the upper rails are band-wheels 12 on which run the belts 12^a, which, according to our present improvement, are constructed of metal or of links 12^b having projections 12^c that engage the cans. 100 The band-wheels, as in the prior construction referred to, can be driven by hand or by other power. A gearing with a hand-crank 13 is shown for this purpose at the forward or left-hand end of the machine, as viewed in Figs. 1 and 2. The paste-belt is also shown to be driven by the same means, a belt 14 running from the shaft of the forward band-wheel 12 to a pulley 14^a on the shaft of the one of the 105 paste-belt wheels 6 to transmit the power. 110

The cans are propelled or drawn through

the machine by the belts 12^a, which act or operate on the cans near their rims or ends. To give pressure to the cans where they take up the labels, those portions of the belts 12^a that 5 act on the cans to roll them along are sagged by means of rollers 15 journaled in frames 15^a hinged to the top rails 1^a and pressed down by springs 15^b secured on cross-pieces 15^c between the top rails 1^a. The rollers 15 are 10 made with grooves 15^d of such depth that the projections 12^e project beyond their peripheries.

Guide-bars 16, secured to the standards supporting the top rails 1^a, can be arranged 15 along each side of the runway to keep the cans always at right angles to their path of motion.

In operation the paste-belt and the can-moving belts are kept in motion. The can 20 (designated 17, Fig. 2) first takes paste off the forward portion of the paste-belt where the latter crosses the runway. As the can rolls along, this paste picks up the forward end of 25 the uppermost or exposed label, which is wrapped about the can by the rearward rolling of the latter, and the further rolling of the can pulls the other or rear end of the label, and because this end of the label contains 30 paste taken from the belt it is secured to the can. The labels of course will ordinarily be long enough to permit the lapping of the rear 35 end of the label on the forward end, which has been attached to the can. As fast as the labels are removed from the label-holder the latter is moved up by the spring 2^b to expose another label in the runway.

We have not described in detail all the parts shown and described in the aforesaid patent issued to Samuel E. and John Morral 40 because some parts of said machine are not

specially germane to the present improvement, and a detailed description of such parts does not appear necessary to an understanding of our particular improvement herein described. For other details of construction of 45 the can-labeling machine shown in said prior patent reference may be had, of course, to said patent.

What we claim and desire to secure by Letters Patent is:

1. In a can labeling machine, the combination of a run way for the can, means whereby a label can be adherently applied to the can as it moves through the run way, a belt having metallic projections to operate on the can as it moves through the runway, a roller to press said metallic projections into contact with the can, said roller being provided with a belt guiding annular groove of a depth to permit the metallic projection of the belt to 55 extend beyond the rim of the roller to act on the can.

2. In a can labeling machine, the combination of a runway for the can, means whereby the label can be adherently applied to the can 65 as it moves through the runway, two belts having metallic projections to operate on the can as it moves through the runway, a roller to press the metallic projections into contact with the can, means for pivotally hanging said roller, said roller being provided with an annular groove for each of said belts and said grooves being of a depth to permit the belts to 70 project beyond the rim of the roller to act on the can.

SAMUEL E. MORRAL.
WILLIAM W. MORRAL.
